US00D460053S

(12) **United States Design Patent** (10) Patent No.: **US D460,053 S**
(45) Date of Patent: **** Jul. 9, 2002**

(54) **REMOTE CONTROLLER FOR INSULIN PUMP**

D446,854 S * 8/2001 Cheney, II et al. D24/111

* cited by examiner

(76) Inventor: **Soo Bong Choi**, #5-908, Youwon Apt., 421-7 Yeonsoo-dong, Chungju-shi, Chungcheongbuk-do (KR)

Primary Examiner—Ted Shooman

Assistant Examiner—Selina Sikder

(74) Attorney, Agent, or Firm—Sheridan Ross P.C.

(**) Term: **14 Years**

(57) **CLAIM**

(21) Appl. No.: **29/145,355**

The ornamental design for a remote controller for insulin pump, as shown and described.

(22) Filed: **Jul. 19, 2001**

DESCRIPTION

(30) **Foreign Application Priority Data**

Jun. 21, 2001 (KR) 2001-16979

FIG. 1 is a perspective view of the remote controller for insulin pump;

(51) LOC (7) Cl. **13-03**

FIG. 2 is a front elevation view of the remote controller for insulin pump;

(52) U.S. Cl. **D13/168**

FIG. 3 is a rear elevation view of the remote controller for insulin pump;

(58) **Field of Search** D10/104, 106,

FIG. 4 is a left side elevation view the remote controller for insulin pump;

D10/108; D13/164, 168, 171; D14/218;

FIG. 5 is a right side elevation view of the remote controller for insulin pump;

128/200.14; 206/305; 340/425.5, 426, 825.31,

FIG. 6 is a top plan view of the remote controller for insulin pump;

825.69, 825.72; 604/19, 48, 65, 67, 207,

FIG. 7 is a bottom plan view of the remote controller for insulin pump; and,

151; D24/133, 138, 169, 184, 185

FIG. 8 is a perspective view of the remote controller for insulin pump of the present invention, showing an alternative embodiment with a lanyard attached, the lanyard being environment and forming no part of the claimed design.
